PLANTER

Horace M. Lansford, 2312 McKinley,
Fort Worth, Tex. 76106

Filed July 5, 1967, Ser. No. 7,716

Term of patent 14 years

(Cl. D35—3)

Fig. 1

Fig. 2

Fig. 3

Fig. 4

FIG. 1 is a perspective view of a planter embodying my new design;

FIG. 2 is a sectional view as seen looking along the lines II—II of FIG. 1;

FIG. 3 is a perspective view of an alternate embodiment of my new design; and

FIG. 4 is a sectional view as seen looking along the lines IV—IV of FIG. 3.

The broken lines representing the tree trunk are shown for illustrative purposes.

I claim:

The ornamental design for a planter, as shown and described.
